UNITED STATES PATENT OFFICE

102,407

DESIGN FOR A STATUE OR SIMILAR ARTICLE

Aatto Z. Annala, Seattle, Wash.

Application March 9, 1936, Serial No. 61,539

Term of patent 7 years

To all whom it may concern:

Be it known that I, Aatto Z. Annala, a citizen of the United States, residing at Seattle, in the county of King and State of Washington, have invented a new, original, and ornamental Design for a Statue or Similar Article, of which the following is a specification, reference being had to the accompanying drawing, forming part thereof.

The frieze shown near the base of the statue extends entirely around the same, the rear figures being substantially the same as those in front although not duplicates thereof.

The figure is a front perspective view of a statue or similar article, showing my new design.

I claim:

The ornamental design for a statue or similar article, as shown and described.

AATTO Z. ANNALA.
